UNITED STATES PATENT OFFICE.

CHARLES L. NORTON, OF NEWTON, MASSACHUSETTS, ASSIGNOR TO REFRactories
MACHINERY MANUFACTURING COMPANY, OF PITTSBURGH, PENNSYLVANIA, A
CORPORATION OF PENNSYLVANIA.

MOLDING MACHINE.

Application filed February 11, 1922. Serial No. 535,732.

To all whom it may concern:

Be it known that I, CHARLES L. NORTON, citizen of the United States of America, and resident of Newton, in the county of 5 Middlesex and State of Massachusetts, have invented new and useful Improvements in Molding Machines, of which the following is a specification.

My invention relates to the manufacture 10 of brick or other shapes, by molding, and is intended for service in particular with such materials as ground ganister and hard clays, which are unresponsive to molding-methods adapted to more plastic materials. 15 In my Letters Patent of the United States, Nos. 1,332,676 and 1,332,677, dated the second day of March 1920, it is pointed out that such materials as ground ganister can be molded by projecting, as by dropping, 20 a charge of the material under such conditions that on arrival at the mold its particles are arranged in a dense swarm, in which each particle is free from contact with its neighbors to such an extent that, 25 though it be narrowly limited, this freedom enables the particles to move in relation to each other and fill the mold, into which they fall with force and emphasis. In applications for United States Letters 30 Patent filed by me on the twenty-fourth day of May, 1921, Serial Nos. 472,244, and 472,245, it is further explained that the completeness with which a mold is filled by the mode described in the aforesaid patents is 35 more fully assured, if the mold-charge liberated from an elevated hopper is slightly smaller in horizontal profile than the mouth of the mold which the charge is to fill, so that particles of material marginal in the 40 descending charge will not be arrested and deflected from a straight trajectory into the mold. In the said applications it is explained also, that the conditions favorable for complete and accurate mold-filling by material of the gritty and refractory character under consideration, both as set forth in my said patents and in the said applications, are still further ensured, if the support, both vertical and lateral, afforded to the aggregate of particles forming the charge of material while it rests in the hopper, be withdrawn simultaneously and abruptly, so that the shape of the charge, imparted to it by the hopper

acting as a matrix, shall be unaltered as 55 little as possible. And, further, it is explained in my said application that, particularly for the purpose of filling large and irregularly shaped molds, it is advantageous to give the hopper, and therefore its charge, 60 a downwardly pointing wedge-shape, so that the charge will enter the mouth of the mold, strike the bottom thereof first, and scatter explosively in all directions.

It may be noted here, that demonstrations 65 and investigations made subsequent to the filing of my said applications have shown that a very acutely pointed falling charge of material, while well adapted to complete mold-filling, is liable to prove over 70 efficient, in that the emphasis of its initial impact strips the mold surface of the light sand-coating with which it is usually prepared, and drives the sand into the lateral regions or recesses of the mold, scouring 75 parts of the mold surface bare, so that the brick shape is liable to stick there and be injured when removed from the mold. The values, and the principle of operation, of the wedge-shaped mold charge are con 80 served, and the incidental disadvantage of the acute wedge-shape removed, by blunting the lower end of the hopper, and therefore of the charges, or, in some cases by providing the bottom of the hopper with a 85 shape which produces two or more salient points, thus distributing the impact and suppressing the scouring action.

The invention herein described is in- 90 cremental and supplemental to those above briefly outlined. Its objects are to perfect, as far as possible, the liberation of the charge from the hopper without derangement of its shape; to adjust, with greater nicety than has heretofore been possible, the 95 degree of dispersion of the material constituting a mold charge, at the instant of entering the mold, and to provide means for increasing or decreasing the velocity of a mold charge as it enters the mold; and to 100 reconcile low dispersion with high velocity. The dominant idea which is exemplified by several specific variations of apparatus and mode of operation in common, is: to cause both hopper and charge to fall together 105 freely, and thus to accelerate the velocity of the charge while holding it undisturbed in the closed hopper, and at some predeter-

mined point in the descent, to cause or to allow the hopper to open and set free the charge, and then to arrest the descent of the hopper, allowing the released charge 5 to continue its course into the mold. The opening of the hopper and the arrest of its fall may be successive or simultaneous; for some purposes it appears to be preferable to open the hopper while it and the charge are 10 accelerating as one, and are, relatively to each other, at rest, so that the opening movement is accompanied by practically no relative movement between these two objects in the gravitational direction; for other purposes it is effective to arrest the hopper and 15 cause the force exerted by the moving charge itself to open the hopper, in such case possibly deranging to some extent the shape imparted to the charge by the hopper, but 20 producing a jet of material from it which, for some mold shapes, works well, provided the hopper be arrested fairly close to the mold. In other cases, especially where wide-mouthed molds of simple shape are to be 25 filled, the arrest of the hopper and its opening movement may be effected simultaneously and with good result.

While the force of gravity constitutes effective means for imparting the desired 30 velocity of movement to the charge, it is obvious that, under some circumstances, as when using certain materials or mold shapes, it might be found desirable to employ some force other than gravity for producing the 35 proper relative movement between the mold and the charge, from which it follows that the movement of the charge would not necessarily need to be in a vertical direction or even that the absolute movement of the 40 charge be at all considerable as compared with that which may be imparted to the mold.

In the drawings hereto annexed, which 45 illustrate my invention, and which show apparatus stripped of structural and contributory accessories as much as possible for the sake of exhibiting clearly the parts which are representative of the operating factors within my invention,

50 Figure 1 is a view in elevation (partly broken away) of a simple apparatus;

Figure 2 is a side view of the same;

Figure 3 is a plan view of the same;

Figure 4 is an end elevation of a more 55 elaborate apparatus;

Figure 5 is a side elevation of the same; and

Fig. 6 is an end view of a modification.

Figure 7 is a sectional plan view of the 60 hopper of Figs. 4, 5 and 6.

Referring to Figs. 1, 2 and 3: A hopper H, consisting of an open ended box, is attached to a drop-board B. Clips C, C, hold the drop board B in sliding relation with 65 the slides S, S. A movable latch P, holds

the hopper H in its upper position. The hopper bottom is closed by a swinging gate G, hinged at an edge at D, and held closed by the catch K, which is mounted on a leaf spring L, secured to the side of the hopper 70 H. An arm A projects from the gate G, and spring R, secured to this arm and to the side of the hopper strains the gate to open.

At a determined point below the upper position of the hopper there is mounted the 75 cam K², which is in place to engage the thumb K' (Fig. 3) on catch K and draw the catch from under the gate G, as the hopper falls. A spring-abutment E, E', E², is secured in such position that it will arrest the 80 hopper board B and therefore the hopper, after the catch K has released gate G, and allowed spring R to jerk it open. Below this abutment the mold M is placed.

The hopper H, latched in its upper position, and with gate G caught closed, is filled with a mold-charge of granular material. Latch P is then withdrawn, and the charged 85 hopper falls, until catch K is drawn by cam K², when the gate G snaps open. The charge does not fall out of the hopper at this instant, since hopper and charge are falling together. But presently the hopper board strikes the spring abutment at E, the 90 hopper is arrested, and the hopper charge O 95 (Fig. 2) shoots downward out of the hopper and into the mold M.

Suppose it were desired to project a charge of material into a mold at the velocity which would be attained after a vertical 100 fall of one hundred feet. (This is a purposely extreme and probably impracticable case, but is exaggerated for purposes of illustration.) If a charge of granulated ganister were released at such a height, the particles, even if guided by a chute or tube, would on arrival at the mold be so scattered that the mold would not be filled. But, by protecting the charge, and conserving its shape and the close aggregation of its particles, by 110 means of a hopper which falls with it, the desired extreme velocity can be acquired, and the charge released from the hopper so close to the mold that its particles arrive in the desired dense swarm.

115 It will now be obvious that a wide range of adjustments of conditions is made possible by the use of apparatus characterized by the factors above described in a very simple example. The slides S may be of any height desired. The releasing cam K² may be placed at any point between the abutment E, E', E² and the upper lodgment of the hopper. The abutment E, E', E² may be spaced as desired in relation to the releasing 120 cam K² or the mold M, or both. A selected velocity, at the instant of release from the hopper, will afford any desired degree of dispersion of granules, according to the distance through which the released charge O 125 130

is to fall freely and without the protecting envelope of the hopper, and, by selecting the height of the starting point of the hopper, any desired emphasis of impact by the 5 charge upon the mold surfaces can be secured.

With the foregoing explanation of the apparatus shown in Figs. 1, 2 and 3, in the reader's mind, a very brief description of 10 Figs. 4, 5 and 6 will suffice.

In Figs. 5 and 6, there is shown a falling hopper with mechanical adjuncts which open and arrest the hopper simultaneously. The hopper is of the "clam shell" type, composed of two similar halves 1, 1, each pivoted by a pin 6 on a frame 2; each also carries a pin 7. Pins 6 and 7 travel in slides 3, and, when the two pins of each half of the hopper are in the straight vertical portions 20 of the slides, the hopper will be closed. Each slide diverges at the bottom, at 5. A spring 8 is stretched between pins 7, 7. A spring abutment at 9 may be provided, to be encountered by the projecting ledge of the 25 frame 2. The mold M is placed below the hopper. The hopper is shown in full lines in both its upper and lower positions.

The hopper being held in its elevated position, it is charged with material, and allowed to fall. Hopper and charge fall together and exert no force on each other (appreciably) during their fall. When pins 7 reach the divergent portions 5 of the slides, the halves of the hopper are opened, and the 35 charge O released. Spring 8 cushions the shock of the hopper, and spring abutment 9 contributes to this cushioning effect. The cushioning springs should be so adjusted that the mechanism of the hopper shall not 40 be unduly wrenched by its arrest.

Any variety of hoisting mechanism may be employed to restore the hopper to its elevated position. The cycle of operations will resemble that of a pile-driver.

45 Referring now to Fig. 6; the hopper is here again of the "clam shell" type, but deep, with a pointed nose. Its two halves 11, 11 are pivoted on pins 13, 13, to a frame 12, and are held together by a spring 15, the function of which is, chiefly, to hold the hopper closed while it is filled, and during 50 its descent. Slides 14 guide the hopper, by means of the pins 13, which run in the slides. An abutment 16 is placed where it 55 will arrest the frame 12 and therefore the hopper.

The hopper 11, 11, being held elevated, it is charged with material, and let fall. When the hopper is arrested by the abutment 16, 60 the momentum of the charge pushes aside the pivoted halves of the hopper against the stress of the spring 15, and shoots it in a jet to and into the mold M.

The method above described is the subject 65 matter of claim in an application for United

States Patent, filed by me concurrently herewith, serially numbered 525,733.

I claim:

1. An apparatus for forming molded shapes comprising an openable container, 70 means whereby such container may be projected toward an open mold, and means for causing said container to open to permit discharge of its contents at a determined distance from the mold. 75

2. Apparatus for forming molded shapes comprising an open mold, an openable hopper, means for guiding said hopper for movement toward the mold, and means for causing said hopper automatically to open 80 at a variably determinable distance from the mold.

3. An apparatus for forming molded shapes comprising means whereby an openable container may be impelled toward an 85 open mold, means for guiding said container in its movement, and adjustable means arranged at a predetermined distance from the mold for causing said container to open whereby to permit discharge of its contents. 90

4. Apparatus for forming molded shapes comprising a mold, an openable hopper, means for guiding said hopper for movement toward the mold, and cam means associated with said guiding means for opening 95 said hopper during the movement thereof, said cam means being adjustable relatively to the mold.

5. Apparatus for molding brick-shapes or the like, comprising a mold, a gravity-slide above the mold, an openable hopper, mounted to fall from a height along the gravity-slide toward the mold, and means for causing the hopper to open at a point on the slide above the mold. 100

6. Apparatus for molding brick-shapes or the like, comprising a mold, a gravity-slide above the mold, an openable hopper mounted to fall from a height along the gravity-slide toward the mold and means to 110 open the hopper while it is in descent toward the mold.

7. Apparatus for molding brick-shapes or the like, comprising a mold, a gravity-slide above the mold, an openable hopper 115 mounted to fall from a height along the gravity-slide toward the mold, means to open the hopper at a point on the slide above the mold, and a stop to arrest the hopper above the mold. 120

8. Apparatus for molding brick-shapes or the like, comprising a mold, a gravity-slide above the mold, an openable hopper mounted to fall from a height along the gravity-slide toward the mold, means to 125 open the hopper at a point on the slide above the mold, and a stop to arrest the hopper above the mold after it has opened.

9. Apparatus for molding brick-shapes or the like, comprising a mold, a gravity- 130

slide above the mold, an openable hopper having downwardly converging separable ends, said hopper being mounted to fall from a height along the gravity-slide toward the mold, and means to arrest the hopper above the mold.

10. Apparatus for molding brick-shapes or the like, comprising a mold, a gravity-slide above the mold, an openable hopper

10 comprising two separable sections, said hopper mounted to fall from a height along the gravity-slide, means to hold the said hopper sections together through the upper portion of its fall, means to separate the sections at 15 a point above the mold, and a stop to arrest the fall of the hopper.

11. Apparatus for forming molded shapes comprising an open mold, an openable hopper of "clam shell" type, having similar 20 halves pivoted to swing apart, means for normally holding said halves together, means for guiding said hopper for movement toward the mold, and means for causing said halves to separate to permit discharge of the hopper contents at a determined distance from the mold.

12. Apparatus for forming molded shapes comprising an open mold, a hopper having complementary parts pivoted to swing away 30 from each other, means for guiding said hopper for movement toward the mold, means operative to prevent separation of said hopper parts during a predetermined extent of such movement of the hopper, and 35 cam means for separating said parts whereby to permit ejection of the contents of the hopper.

13. Apparatus for forming molded shapes comprising a mold, a hopper having relatively movable parts, each of said parts be- 40

ing provided with an outstanding pin, and a guide for directing said hopper in moving toward the mold, said guide having spaced slots for the reception of the respective pins, and cam means associated with 45 said slots constructed and arranged to cause separation of said pins whereby relatively to move the parts of the hopper to permit discharge of the contents thereof.

14. Apparatus of the class described comprising a hopper of the "clam shell" type having complementary halves pivoted to swing apart, a pair of guideways for guiding said hopper for movement toward a mold, said guideways being substantially 55 parallel throughout the major portions of their lengths, but diverging from one another at points adjacent to the mold, a pin 60 projecting from each half of the hopper and engaging one of the respective guideways, and means adjacent to the diverging portions of the guideways for arresting movement of the hopper.

15. Apparatus for forming molded shapes comprising a mold, means for projecting a 65 container for material toward said mold, and means for resiliently arresting the movement of said container whereby to permit discharge of the contents thereof into the mold.

16. Apparatus of the class described comprising an open mold, means whereby an openable hopper may be projected toward the mold, means for opening said hopper at a determinate point in its path of movement, and means for resiliently arresting the movement of the hopper.

Signed by me at Boston, Massachusetts, this seventh day of February, 1922.

CHARLES L. NORTON.
